UNITED STATES PATENT OFFICE.

HUGH KENNEDY, OF SHARPSBURG, PENNSYLVANIA.

STACK-CONNECTION FOR HOT-BLAST STOVES.

SPECIFICATION forming part of Letters Patent No. 369,342, dated September 6, 1887.
Application filed January 10, 1887. Serial No. 223,914. (No model.)

To all whom it may concern:

Be it known that I, HUGH KENNEDY, of Sharpsburg, in the county of Allegheny and State of Pennsylvania, have invented a new and useful Improvement in Stack-Connections for Hot-Blast Stoves; and I do hereby declare the following to be a full, clear, and exact description thereof.

Great difficulty has heretofore been experienced in the use of the valves which control the stack-flue of hot-blast stoves. When a stove is "on gas," the heated gases passing over the valve on their way to the stack heat the valve and the stack-flue up to a very high temperature, so that it is necessary, in order to preserve the valve and its seat, to provide them with water-cooling devices; but this provision does not prevent the valve and its seat from becoming warped by the great extremes of temperatures through which the various changes in the currents of the stove cause them to pass. The result is, the valve is seldom tight, and the leakage is constantly increasing as the period of its use lengthens. A very serious evil arising from this leakiness of the valve is experienced when the stove is "on air," because the pressure of the blast forces the air through the leaky valve into the stack-flue and destroys or injuriously affects the draft in the other stoves which are connected with the same stack. There are always several stoves connected with a single stack, and as the air is under pressure and the wasted heat is not, the draft through the leaky valve is sufficient in many instances to make a serious defect in the operations of the stoves which are "on gas" and connected with the same stack.

My invention is designed to obviate these difficulties, and its principal advantages are that it enables me to dispense with a stack-flue valve and completely prevents any interference on the part of a stove "on air" with the stoves which are "on gas."

To enable those skilled in the art to make and use my invention, I will now describe it with reference to the accompanying drawings, in which—

Figure 1 is a vertical sectional view illustrating the simple form of my improvement. Fig. 2 is a vertical section of my improvement as applied to the existing stove, and Fig. 3 is

a side elevation of a portion of the stove and of the stack-flue.

Like letters of reference indicate like parts.

In the drawings, *a* indicates the side of the hot-blast stove containing the opening *b*, which leads to the stack-flue, and *c* is the pipe or flue which connects the opening *b* with the stack-flue *d*. The opening *b* is faced with a suitable casting, *e*, which may have a ground-seat, *e'*, for receiving the beveled end of the pipe *c*. The pipe *c* is composed of a fixed or stationary section, *c'*, and a moving or telescoping section or end, *c''*, which is capable of being moved back and forth in the fixed section *c'* by means of handles *c''*, so as to connect or disconnect the pipe *c* with the opening *b*.

The stove is provided with a sliding door or lid, *f*, for closing the opening *b* when the pipe *c* is disconnected therefrom, and this door *f*, when the pipe *c* is connected with the opening *b*, may be fastened out of the way by means of the hook *g* engaging with the staple *f'*; or, if desired, the door may slide laterally or be removable. This, however, is an immaterial matter of construction, as any form of device which will close the opening *b* tightly when the stove is "on air" and the pipe *c* is disconnected is all that is necessary.

When the pipe *c* is connected with the stove, it may be fastened by means of straps *h*, hinged to the side of the stove and engaging with lugs *i*, to which they are secured by keys *k*, passing through the straps and bearing against the lugs, as shown by the broken lines in Fig. 2 and by full lines in Fig. 3. When the pipe *c* is disconnected, the end of the section *c''* may be closed by a suitable cap, *m*, which is secured thereto by straps *n* and keys *n'*, the purpose of which is to prevent a current of cold air from being drawn into the stack-flue through the open end of the pipe *c*. Any other suitable device for closing the end of the pipe *c* when disconnected from the stove may be used. For instance, in Figs. 2 and 3 I show the application of my improvement to the stove already fitted with a valve, *o*. As ordinarily constructed, the presence of this valve does no harm. It acts as well to close the pipe *c* when disconnected from the stove as any other form of cap, and, being there, it is not necessary to remove it.

95
100

Thus constructed, the operation of my improvement is as follows: When a stove is "on gas," the pipe *c* is connected with the opening *b*, as shown in Fig. 2 of the drawings, and the gas passes through the opening *b* and pipe *c* to the stack-flue in the usual way. When it is desired to reverse the stove, the fastening devices are loosed, the telescoping end of the pipe *c* is drawn back, so as to completely disconnect it from the stove, the door *f* is lowered so as to close the opening *b*, and the pipe *c* is closed by means of the cap *m*, valve *o*, or other suitable closing device.

It is apparent that there is no danger of the air from the stove blowing into the stack-flue *d* when the pipe *c* is disconnected and the opening *b* closed, and if the opening *b* does leak by reason of the door *f* not fitting closely, no harm is done, except that a small portion of the blast is wasted. It is also apparent that, as the air (the blast) cannot obtain access to the pipe *c*, no valve is necessary, and that any suitable device for closing the pipe *c* will answer in lieu thereof. Thus I am enabled by my invention to take away one of the most fruitful causes of irregularity in the action of these stoves, and to dispense with one of the most troublesome and expensive features in connection therewith.

I do not limit myself to the particular form of device shown and described for connecting and disconnecting the stove and stack-flue, because it will be apparent to the skilled mechanic that the pipe *c* may be hinged and swing

laterally, or that a portion of the same may be capable of entire disconnection from the other parts. When it is desirable to close the stove, such disconnected part may be lifted off and laid to one side.

Other obvious modifications may be suggested, all of which involve the principle of complete separation between the stove and stack-flue whenever desired.

It is apparent that the fixed part of the pipe *c* may be connected with the stove and the movable part in connection with the stack-flue. This arrangement, which would be merely turning my invention around, is not, however, so good as the arrangement illustrated in the drawings.

I do not limit my invention to hot-blast stoves, but include, also, other combustion-chambers which require a valve between the chamber and the stack.

What I claim as my invention, and desire to secure by Letters Patent, is—

The combination of the hot-blast stove with a stack-flue and an intermediate connection-pipe capable of being detached from the stove or flue, substantially as and for the purposes described.

In testimony whereof I have hereunto set my hand this 6th day of January, A. D. 1887.

HUGH KENNEDY.
